(57) **CLAIM**

The design for an overhead carriage for vehicle washer, substantially as shown and described.

DESCRIPTION

FIG. 1 is a first perspective view of an overhead carriage for a vehicle washer showing our new design;

FIG. 2 is a second perspective view thereof;

FIG. 3 is a front elevational view thereof;

FIG. 4 is a top plan view thereof;

FIG. 5 is an enlarged side elevational view thereof;

FIG. 6 is a rear elevational view thereof; and,

FIG. 7 is a bottom plan view thereof.

The broken line showing of a double-spray arm in FIG. 1 and a single spray arm in FIG. 2 is included for the purpose of showing environmental portions of the overhead carriage for a vehicle washer and forms no part of the claimed design. The broken line showing of a hole in FIG. 7 also shows an environmental portion of the overhead carriage for a vehicle washer, particularly an opening to permit connection of the spray arm or arms shown in broken line in FIG. 1, and forms no part of the claimed design.
